UNITED STATES PATENT OFFICE.

ALBERT DUMONT, OF DETROIT, MICHIGAN.

RAIL-CLAMP.

1,235,775.

Specification of Letters Patent.

Patented Aug. 7, 1917.

Application filed April 9, 1917. Serial No. 160,821.

To all whom it may concern:

Be it known that I, ALBERT DUMONT, a citizen of the United States, residing at Detroit, in the county of Wayne and State of Michigan, have invented certain new and useful Improvements in Rail-Clamps; and I do declare the following to be a full, clear, and exact description of the invention, such as will enable others skilled in the art to 10 which it appertains to make and use the same.

This invention relates generally to railroad appliances, and more particularly to certain new and useful improvements in 15 rail clamps.

The primary object of the invention is to provide a means whereby the ends of two adjacent rails may be firmly clamped together without the use of bolts or other similar loose securing elements.

Another object of the invention is to provide a rail clamp, the greater portion of which is disposed beneath the flange of the rail and thus out of the way of the wheels 25 of the trains, and also in such a position that will not invite meddlesome persons to interfere with the same or attempt to separate its component parts.

A still further object of the invention 30 is to improve upon devices of this general character by the provision of an extremely simple, strong, durable and inexpensive construction, one which will be efficient and reliable in operation, and well adapted to 35 the purpose for which it is designed.

With these and numerous other objects in view, the invention consists of certain novel features of construction and the combination and arrangement of parts which 40 will be hereinafter fully described and claimed.

In the accompanying drawing wherein the preferred form of the invention is illustrated:

45 Figure 1 is a side elevation of a device constructed in accordance with this invention, showing it in clamped relation with the ends of a pair of adjacent rail sections;

50 Fig. 2 is a transverse sectional view of the device applied to the rail, taken on the plane indicated by the line 2—2 of Fig. 1; and

55 Fig. 3 is a longitudinal sectional view taken on the plane indicated by the line 3—3 of Fig. 2.

In specifically describing the structure shown in the drawings above briefly described, similar reference characters will be used to designate like parts throughout the several views, and reference will be herein 60 made to the various elements by their respective indices. To this end, the letters A, A represent the ends of a pair of adjacent rail sections, which are of the usual construction having a tread flange a, base flange 65 b and a vertical web c connecting the two flanges. Obviously, these parts form no part of the present invention, and are merely shown and described for the purpose of making the use and construction of the present invention clear.

The reference numerals 1 and 2 represent a pair of clamp members, the member 1 being provided at its edges with inwardly extending lugs 3 having alined apertures 4 75 therein, while the member 2 is provided intermediate of its edges with a lug 5 also having an aperture 6 therein. The lug 5 is disposed between the lugs 3, the aperture 6 being alined with the apertures 4, 80 and a pivot pin 7 is then inserted through these apertures to hinge the two members together. As shown, they are hinged together at a point intermediate their upper 85 and lower ends.

The inner sides of the upper ends of the members 1 and 2 engage the opposite sides of the web c of the rails and are provided with opposing recesses 8 which receive the opposite sides of the base flange b.

To prevent the clamp from moving longitudinally along the rail, a small stud or pin 9 carried by the member 1 is inserted in an opening d in the web of the rail. This pin 9 may be formed as an integral part of 95 the member 1, or it may, as here shown, be driven into a socket arranged in said member.

The inner sides of the lower ends of the members 1 and 2 are provided with opposing recesses 10, which are substantially semi-circular in section in order to provide for the reception of a wedge member. This wedge member consists of a longitudinal pin 11, which is greater in diameter than the 100 distance between the opposite walls of the recesses 10 when the members 1 and 2 are in position upon the rail ready to be clamped, but not actually clamped. One end of the pin 11 is provided with an ab- 105 110

rupt taper 12 which is sufficient to expand the lower ends of the members 1 and 2 to allow the pin 11 to be driven between the same, and when this is done, the upper 5 ends of the members are moved into their clamping position.

In applying the attachment to use, the two members while in separated condition, that is, with the pin 11 removed, are disposed on opposite sides of the rails. The pin 7 is then inserted in place, and when it is desired to clamp the ends of the rail sections together, the pin 11 is driven into place.

15. It will be seen that the hinge and wedge member are disposed directly beneath the central portion of the rail, and hence there are no projecting or protruding members to become broken. Furthermore, in such position the separable members will not become readily detached or invite meddlesome persons to interfere with and detach the same.

From the foregoing description, taken in 25 connection with the accompanying drawings, the construction, use and operation of the device will be readily understood without a more extended explanation.

As various changes in form, proportion, 30 and in the minor details of construction may be resorted to without departing from the spirit of this invention, it is to be understood that I do not wish to be limited to the precise construction herein shown and described.

I claim:—

1. A device of the class described comprising a pair of clamp members hinged together between their ends, one of the ends 40 of said members being adapted to engage the opposite sides of the rail, and means for relatively expanding the other ends of said member so as to move their first mentioned ends into clamping position.

45. 2. A device of the class described comprising a pair of clamp members hinged together between their ends, one of the ends of said members being adapted to engage the opposite sides of the rail, and a wedge 50 member inserted between the other ends of said members to relatively expand said other

ends so as to move their first mentioned ends into clamping position.

3. A device of the class described comprising a pair of clamp members hinged together between their ends, one of the ends of said members being adapted to engage the opposite sides of the rail, and a pin inserted longitudinally between the other ends of said members to relatively expand said other ends so as to move their first mentioned ends into clamping position.

4. A device of the class described comprising a pair of clamp members hinged together between their ends, one of the ends 65 of said members being adapted to engage the opposite sides of the rail, the inner faces of the other ends of said members being provided with opposing recesses, and a pin inserted longitudinally between the said 70 other ends of said members to relatively expand said other ends so as to move their first mentioned ends into clamping position.

5. A device of the class described comprising a pair of clamp members hinged together between their ends, the inner sides 75 of one of the ends of said members being adapted to engage the opposite sides of the web of the rail and being provided with opposing recesses to receive the base flange 80 thereof, and means for relatively expanding the other ends of said members so as to move their first mentioned ends into clamping position.

6. The combination with a rail joint, of a 85 clamp composed of a pair of clamp members hinged together between their ends, one of the ends of said members engaging the opposite sides of said rail, and a wedge pin inserted between the other ends of said 90 members for relatively expanding said other ends so as to move their first mentioned ends into clamping position, the hinge of said member and said pin being disposed directly beneath the rail.

In testimony whereof I have hereunto set my hand in the presence of two subscribing witnesses.

ALBERT DUMONT.
